UNITED STATES PATENT OFFICE.

JOHN F. DUNN, OF NEW YORK, N. Y.

BUTTON-FASTENING DEVICE.

SPECIFICATION forming part of Letters Patent No. 608,588, dated August 9, 1898.

Application filed March 20, 1897. Serial No. 628,429. (No model.)

To all whom it may concern:

Be it known that I, JOHN F. DUNN, of the city, county, and State of New York, have invented a new and useful Improvement in Button-Fastening Devices, of which the following is a specification.

The present invention relates to a new and improved button-fastening device.

In the drawings I have shown my invention as illustrated in a button, in which—

Figure 1 is an elevation view, and Fig. 2 is an inverted plan showing the shank of the button in section.

Like letters of reference refer to like parts in both views.

Referring to said drawings in detail, A represents the head of the button; B, the shank; C, the securing device, and D the fabric to which the button is attached.

The fastening or securing device C, as illustrated, consists of two U-shaped parts secured together, so as to turn relatively to each other about a pivot c, each U-shaped part comprising arms c' and c² and having a cut-out portion c³, adapted to fit the inner surface of the shank B. The arms c² are each provided with a projecting portion c⁴, forming finger-pieces. The mode of using the device will be apparent. The fabric or other article to which the securing device is to be attached being provided with a hole, the shank B is passed through. The securing device is then manipulated so that the arms c' c² are all parallel, the arms c² lying on each other, in which position the arms c³ are passed through the eye of the shank and are

then spread out, as seen in Fig. 2, in which position they remain by the friction of the parts and by the shank resting in the cut-out portions c³.

If it is desired to move the securing-piece, the arms c² are pressed together until they lie on each other, when they may be passed through the eye of the shank.

What I claim is—

1. A fastening device, for buttons having a shank provided with an opening, composed of two parts substantially U-shaped in contour and movably secured one upon the other, said parts being adapted to be inserted in the opening of the shank so as to have their curved portions fitting therein and to have their ends extend in opposite directions, substantially as described.

2. A fastening for buttons or other securing devices which have a shank provided with an opening, composed of two U-shaped parts movably pivoted one upon the other and each provided with a recess or cut-out in its curved portion, said recess or cut-out in each of the curved parts being adapted when the device is in locked position to be within the shank and engaging it, and to have their ends extending in opposite directions, substantially as described.

In testimony whereof I have signed my name to this specification in the presence of two subscribing witnesses.

JOHN F. DUNN.
